UNITED STATES PATENT OFFICE.

GEORGE M. CHENEY, OF SOUTHBIDGE, MASSACHUSETTS, ASSIGNOR TO LITCHFIELD SHUTTLE COMPANY, OF SOUTHERIDGE, MASSACHUSETTS, A CORPORATION OF MASSACHUSETTS.

SHUTTLE FOR AUTOMATIC LOOMS.

Application filed August 13, 1923. Serial No. 657,139.

To all whom it may concern:

Be it known that I, GEORGE M. CHENEY, a citizen of the United States, and resident of Southbridge, in the county of Worcester and State of Massachusetts, have invented certain new and useful Improvements in Shuttles for Automatic Looms, of which the following is a specification.

This invention relates to shuttles and especially to that type of shuttles used in automatic looms which are provided at the rear or heel end with a deflector plate or member for guiding the bobbin into the spring fork which grips and holds the bobbin axially in the shuttle for the weaving operation.

As the successive bobbins fed into the shuttle are driven from the bobbin magazine into the shuttle by a forcible blow or impact from the hammer, the forwardly and downwardly inclined deflector is subjected to repeated sharp blows or shocks which produce strains and vibrations tending to cause the deflector and its fastening or anchoring screw, as well as other parts, to work loose and thus interfere with the operation of accurately feeding the bobbin into the shuttle.

The present invention is intended to overcome the above described trouble and other difficulties besides by providing an anchoring and supporting means for the fork and for the deflector that minimizes these faults. The invention consists in applying to the deflector securing means which maintain a continual tension capable of yielding slightly to absorb the shocks while maintaining a constant contact between the securing means and the deflector. The same principle is also applied to anchoring the spring fork securely in proper position.

These and other features of the invention will be explained in the following specification and will be defined in the claims hereto annexed.

In the accompanying drawings I have illustrated the preferred construction and arrangement embodying the principles of this invention, in which:

Figure 1 is a plan view of the rear or heel end of the shuttle properly machined to receive the bobbin fork deflector and other parts with the vertical anchoring bolt shown in horizontal section directly below its head.

Figure 2 is a plan view of the rear portion of the shuttle showing the spring fork bob-

bin deflector and the anchoring members in their normal operative position.

Figure 3 is a central vertical section through the parts shown in Figure 2.

Figure 4 is a horizontal section on the plane of the transverse anchoring bolt.

Figure 5 is a vertical cross section showing the base of the bobbin secured in its holding fork.

Figure 6 is a plan view of the deflector reinforcing plate.

Figures 7 and 8 are perspective views of the self-locking nut and washer used on the anchoring bolts.

Figure 9 is a perspective of the tension device or spring washer.

Figure 10 is a detail view showing in plan, partly broken away, the bobbin deflector plate.

Figures 11 and 12 show a modified form of reinforcing plate.

In the practice of this invention, according to the construction and arrangement illustrated in the drawings, the heel or rear end of the shuttle 1, is provided with a shallow U-shaped recess 2, formed in the top of the shuttle for the reception of the upper leg or arm of the deflector plate, and its forward interior portion is cut away to a substantially greater depth to form a small and tapered recess 3, for the reception of the rear end portion of the bobbin-holding fork. The floor or bottom of the recess 3 is extended forwardly to the front edge of the heel end of the shuttle to form a supporting shelf or ledge 4 which supports the downward thrust of the spring fork 5.

The spring fork 5, is of a usual construction comprising an integral strip of heavy spring metal doubled back upon itself at the middle portion to form a relatively narrow slotted shank 5^a whose forward ends diverge and extend forwardly to form the spring arms for gripping the rings 15, formed on the base of the bobbin 16. At their outer end portions the spring arms of the fork are vertically corrugated to form recesses 5^b to register with the retaining rings on the bobbin.

To protect the thrust-supporting wall 4, as well as to deflect or guide the entering bobbin so that its ring will be in proper alignment with the receiving slots 5^b, the deflector member 6 is employed. This com-

prises an upper arm 6^a and a lower arm 6^b, with an intermediate inclined or sloping portion 6^c, which acts as the deflector for guiding the bobbin. To support the deflector 5 against buckling under the repeated blows of the bobbins striking against it at the middle portion of the inclined or sloping guide face c, I provide a special reenforcing member 7, terminating at its front in a straight 10 edge projecting across the space between the separated arms of the fork in line with the crease or bend at the juncture of the top portion 6^a, and the inclined portion 6^c of the deflector plate.

15 To give additional firmness and solidity to the fork there is usually employed a wedge member or plug 8 which is forced into the narrow recess in the shank portion of the bobbin fork. In this case the wedge 20 is made somewhat deeper vertically than the depth of the shank portion of the fork, and is rabbeted or cut away at its front edge so as to leave a projecting guide portion 8^a, formed to fit into the slot in the rear or tail 25 member 7^b, of the bridge plate 7. The middle portion of the transverse bridge 7 rests on the shoulder formed by cutting away the forward part of the wedge so that a firm 30 support is given to the entire forwardly projecting or overhanging portion of the upper arm of the deflector to prevent it from buckling or bending. As the top surface of the key member 8^a, and the bridge plate 7, are flush with each other they form a continuous level supporting surface for the under side of the upper arm 6^a, of the deflector. The lower arm 6^b, forms a level 35 surface for supporting the flush bottom faces of the fork and of the wedge and prevents them from indenting the wooden wall or floor beneath.

40 As shown in Figures 1, 2, 3 and 5, the side walls of the shuttle toward the rear part that embrace the divergent arms of the fork 5, are undercut to form narrow overhanging ledges 1^a, which ledges, as shown in Figures 2 and 3, form a positive stop or anchorage against any tilting upward of the forward ends of the bobbin 45 fork since the fork, at its widest point, passes under these ledges and any such upward thrust would be transmitted through the side edges of the bridge plate 7 against the bottom of said ledges or shoulders. 50 Since the bottom floor 4 of this portion of the shuttle prevents any downward tilting in the forward end of the fork, the fork is securely anchored against any possible pivotal movement about its transverse retaining 55 bolt 12.

60 It will also be seen that the forcible thrust of the bobbin against the inclined portion 6^c of the deflector plate 6 is transmitted through the bridge plate 7 to the underlying portion of the wedge block 8, pro-

jecting beneath said bridge plate instead of, as heretofore, transmitting the entire shock upon the arms of the fork itself.

65 The parts thus assembled are obviously very liable to loosening or working out of position, not only under the repeated shocks and vibrations imparted by the blows of the loom picker-stick against the ends of the shuttle, but also because of the heavy impact of the butt or base of the bobbin as it is 70 forcibly driven into the shuttle to replace an empty bobbin, and much loss and inconvenience has been caused by the loosening of the assembled parts.

75 According to my present invention the parts are securely anchored by vertical and transverse anchoring elements which are constantly kept under heavy spring tension, while the fastening elements are also held or secured in rotative movement by their own 80 axes.

85 As shown in Figures 2 and 3, the upper arm of the bobbin-deflecting and fork-retaining plate is extended rearwardly and is provided with a countersunk perforation as 90 shown at 6^d, the perforation being made of an irregular form, in this case a keyhole slot, to prevent rotation of the bolt passed through it. The vertical anchoring bolt 9 has its underside inwardly bevelled and at 95 one point is provided with a web or fin 9^a, to engage the eccentric notch formed in the perforation 6^d. To keep the bolt constantly under tension I employ a split washer 10, with its adjacent ends axially offset and with at least one face preferably provided with 100 corrugations 10^a, which are indented into the wood and assist in preventing rotation of the bolt 9.

105 The corrugated spring washer is placed around the upper edge of the vertical bolt hole in the shuttle body with the opening between its ends aligned with the eccentric notch formed in the plate perforation 6^d. The washer is placed in position before the 110 deflector and fork are assembled in operative position so as to lie beneath the plate and exert a strong upward tension thereon, the corrugated side being turned downward to engage the underlying portion of the wood 115 of the shuttle. The bolt is then inserted with its threaded end projecting into the bottom slot of a countersunk recess and an automatically locked nut 13 with its locking washer 11, are placed over the thread end and tightened until the corrugations 11^a of the washer are embedded in the exposed surface of the wood surrounding the bolt hole. The opposite face of the washer 11 is provided with radial grooves or recesses 11^b, 120 which receive and interlock with corresponding ribs 13^a formed on the opposed face of the nut. 125

130 From the foregoing it will be seen, first that the deflector plate rests on the com-

pressed spring at its rear anchored end and sustains the downward strain or thrust of the anchoring bolt, while the anchoring bolt is positively held against rotation by means of its interlocking engagement with the recess in the deflector plate and is itself kept under constant tension by the compressed spring washer. At the other end of the bolt, the self-locking nut, engaging its corrugated interlocking washer, is held against rotation since the projecting ribs on the washer are embedded in the wood under a strong tension. The result is a slight cushioning of each shock or impact and constant locking tension which prevents any working loose of the parts.

A transverse fastening element is made on exactly the same principle and comprises a bolt 12, having underneath its head a locking fin 12^a resting against a spring washer 10, exactly like that already described, while at its other end an interlocking nut 13 and washer 11, precisely like that already described, is employed to prevent rotation under the influence of rapid vibration.

Therefore, the combination of the continuous spring tension with the self-locking elements of the fastening means act to overcome the troublesome tendency of the parts to work loose so long as the shuttle itself remains in good serviceable condition. At the same time the parts can be disassembled by means of a socket wrench applied to the locking nuts with sufficient force to turn them against their locking or holding means, since the spring will yield sufficiently to allow such disengagement while maintaining a positive lock as against any mere accidental rotation due to vibration or shock.

In Figures 11 and 12 are shown a slightly modified form of bridge plate in which the body portion 17, of the bridge plate, is not slotted or perforated to receive the projecting fins shown in 8^a, but simply lies flat over the top face of the wedge block 8 which is flush with the top surface of the bobbin fork. The body portion 17 of this bridge plate has lateral forwardly projecting extensions or arms 17^a, which pass beneath the ledges 1^a at the top of the shuttle and engage the undercut side walls. In this case both the widest portion of the fork and the widest portion of the bridge plate are sustained by the side walls against any lateral displacement or torsional displacement in a horizontal plane, while these two members, being snugly interposed between the floor or bottom 4 of the shuttle body and the overhanging ledges or shoulders 1^a, are positively anchored against any vertical displacement or turning. With this construction the transverse locking bolt 12 may be dispensed with entirely if desired since the vertical bolt 9 serves to prevent any longitudinal displacement and any other possible displace-

ment is taken care of by the supporting portion of the shuttle body itself. With this in view the wedge block 18 is shown without any perforation and without any upwardly projecting rib, similar to 8^a, to penetrate a slot in the bridge plate.

What I claim is:

1. In a loom shuttle, the combination of a bobbin fork, a cooperating fork-supporting and bobbin-deflecting member having an upper arm extending rearwardly beyond the fork and provided with a bolt-receiving and locking perforation, an anchoring bolt passed through said perforation and the underlying portion of the shuttle body, a self-locked nut secured to the other end of the bolt, and a compressive spring located beneath the said perforated extension of the bobbin-deflecting member to exert an upward yielding thrust against the underside of the said extension and maintain the nut constantly in locked relation while allowing the nut to be manually released, substantially as described.

2. In a loom shuttle, the combination of a fork-holding bobbin-deflecting member provided with a rearward perforated attaching extension overhanging the solid heel portion of the shuttle, a compression spring interposed between said extension and the underlying part of the shuttle body, an interlocked bolt passed through said perforation and the shuttle body, and a lock nut secured to the lower end of said bolt and acting through the bolt to compress said rearward extension upon said spring, substantially as described.

3. In a loom shuttle, the combination of a fork-embracing bobbin-deflecting plate provided with a perforated rearward extension overlying the solid heel portion of the shuttle body, and fastening means passed through said perforated extension and the underlying portion of the shuttle body and acting to draw said rearward extension firmly against a yielding supporting member, substantially as described.

4. In a loom shuttle, the combination of a fork-embracing bobbin-deflecting member and fastening means embracing a bolt provided with a torsion-resisting portion arranged to interlock with a bolt hole in said member to prevent its rotation in the shuttle body, bolt-tensioning means forming an intermediate connection between the torsion-preventing member and the shuttle body, and a self-locking nut secured in the opposite end and maintained in locked relation to the shuttle by said tensioning means, substantially as described.

5. In a loom shuttle, the combination of a bobbin fork, a fork-embracing deflector and fastening members passing vertically and laterally through the shuttle body each member being provided with torsion-pre-

venting means and tensioning devices forming a locking connection between the body of the shuttle and said fastening members, one of said tensioning devices also being arranged to exert a yielding pressure against a rearward extension of the deflector, substantially as described.

6. In a loom shuttle, the combination with a bobbin fork and a deflector comprising upper and lower fork-embracing arms and an intermediate forwardly inclined deflector portion, a bridge member interposed between the upper face of the fork and the upper arm of the deflector and comprising a nar-

row rearward portion imposed upon the 15 narrow portion of the fork, and a relatively wide forward portion whose front edge extends across both arms of the fork and beneath overhanging ledges of the shuttle body to form a re-enforcing bridge to support the 20 entire width of the deflector and positively anchor the fork against upward movement at its forward end, substantially as described.

In witness whereof, I have subscribed the 25 above specification.

GEORGE M. CHENEY.
